US00D864838S

(12) **United States Design Patent** (10) **Patent No.:** **US D864,838 S**
(45) **Date of Patent:** **** Oct. 29, 2019**

(54) **WAKE DIVERTER**

(71) Applicant: **Mission LLC**, Minnetonka, MN (US)

(72) Inventors: **Kristopher William Clover**,
Minnetonka, MN (US); **Mark**
Raymond Bohlig, Minnetonka, MN
(US)

(73) Assignee: **MISSION LLC**, Plymouth, MN (US)

(**) Term: **15 Years**

(21) Appl. No.: **29/559,123**

(22) Filed: **Mar. 24, 2016**

(51) LOC (12) Cl. **12-06**

(52) U.S. Cl.

USPC **D12/317**

(58) **Field of Classification Search**

USPC **D12/300-318**

CPC **A63B 69/00; B63C 11/46; B63B 1/16;**

B63B 1/20; B63B 1/22; B63B 1/32

See application file for complete search history.

(57) **CLAIM**

The ornamental design for a wake diverter, as shown and described.

DESCRIPTION

FIG. 1 is a side view of a wake diverter.

FIG. 2 is a top view of the wake diverter.

FIG. 3 is a bottom view of the wake diverter.

FIG. 4 is a rear view of the wake diverter.

FIG. 5 is a front view of the wake diverter.

FIG. 6 is a first bottom perspective view of the wake diverter.

FIG. 7 is a first top perspective view of the wake diverter.

FIG. 8 is a second bottom perspective view of the wake diverter; and,

FIG. 9 is a second top perspective view of the wake diverter. The broken lines shown are included for the purpose of illustrating portions of the article which form no part of the claimed design. The broken lines immediately adjacent the shaded areas represent the bounds of the claim which form no part of the claimed design.

1 Claim, 9 Drawing Sheets
